(57) **CLAIM**

The ornamental design for a bakeware set, as shown and described.

DESCRIPTION

FIG. 1 is a perspective view of a bakeware set showing my new design;

FIG. 2 is a front view thereof;

FIG. 3 is a rear view thereof;

FIG. 4 is a side view thereof;

FIG. 5 is a second side view thereof;

FIG. 6 is a top view thereof;

FIG. 7 is a bottom view thereof; and,

FIG. 8 is a cross-section view taken along line 8-8 of FIG. 6.

The shade lines in the Figures show contour and not surface ornamentation.

1 Claim, 6 Drawing Sheets
